COLLAPSIBLE FUNNEL

Rufus Bibb Lillard, El Paso, Tex.

Application May 11, 1931. Serial No. 536,589

6 Claims. (Cl. 226—38)

The present invention relates generally to funnels and more particularly to collapsible funnels.

It has been proposed heretofore to construct collapsible funnels in certain ways, most of which made the manufacturing cost of such funnels relatively much higher than of usual non-collapsible funnels. Also, many of such proposed funnels had objectionable joints at which leakage often occurred after some use of the funnel. Other proposed collapsible funnels were made of some impermanent fabric or flexible material which deteriorated while kept in stock by the dealer and while in use by the purchaser.

It is an object of my invention to provide a collapsible funnel that can be manufactured and sold for a relatively small sum. It is another object of my invention to provide a collapsible funnel of permanent material that will be without joints that can easily cause leakage of liquids poured through the funnel.

A further object of my invention is the provision of a funnel which is capable of serving as a container for carrying liquids such as gasoline or water.

In carrying out my invention I provide a funnel of thin, pliable metal that can be quickly and easily collapsed, and thereafter easily spread open to have an operative form.

Other features and advantages will appear hereinafter.

Referring to the drawing which forms a part of this specification, Figure 1 is a perspective view of a funnel embodying my invention and illustrating how it can be used as a container.

Figure 2 is a sectional view of the funnel shown in Figure 1, the funnel being shown in substantially flat or collapsed form.

Figure 3 is a side view partly in perspective illustrating one way that my funnel may be employed with a well known kind of oil can.

Figure 4 is a cross section along the line 4—4 of Figure 3.

According to one way my invention may be carried out, a funnel generally designated as 10 may have a conical body or bowl portion 11, an integral tubular stem or spout portion 12 and two integral ear portions 13 each having a hole 14 therethrough for a purpose to presently appear. All of the above named parts may be made of some thin, pliable metal like so-called "white metal" or copper, or of some suitable alloy of copper or tin. When the funnel 10 is opened out for ordinary use it will have the

general appearance of a usual non-collapsible funnel.

Many motorists, especially when touring, carry along in each of their cars, a funnel and a pail of some kind for carrying gasoline in case their supply is exhausted or for carrying water to their radiator, should the water in it run low. An ordinary pail or can and a usual funnel take up a considerable amount of space in the compartment of an automobile provided for carrying such things as tools, etc. Often, as when considerable luggage is carried on a long automobile trip, space in such a compartment is at a premium.

A feature of the present invention resides in the provision of a collapsible device which will occupy only a small amount of space in an automobile tool compartment, such as noted above, and which will serve as a container or pail for carrying a liquid such as gasoline to an automobile and also as a funnel for pouring the gasoline directly into the gasoline tank of the automobile without changing the gasoline from the container before it begins to flow into the tank.

In carrying out this last named feature, the stem portion 12 is made longer than would ordinarily be done if the funnel device were made to serve only as a funnel. Also, the metal wall of the neck is made very flexible whereby its lower end portion may be folded or rolled up in the way illustrated in Figure 1. This rolling up operation may be performed similarly to the way the lower end of a partly emptied tube of tooth paste is rolled up to force all of the remaining paste upward near the mouth of the tube. After the lower end of the stem 12 is rolled up a short distance, it should be wrapped and tied with a piece 15 of cord or flexible wire. The lower end of the stem can be tightly closed by the above described simple operation and then the funnel 10 when sufficiently large, as will usually be the case, can serve satisfactorily as a pail for carrying a considerable quantity of even thin liquids such as water or gasoline.

A handle device for a liquid container or pail made from the funnel 10 as described above can be provided by simply inserting a short stick S through the holes 14 in the ears 13. Then a hand of a person can grasp the stick between the ears 13 and carry the funnel-container very conveniently. If desired, a wire bail of a well known kind may be used with the funnel in place of the stick S.

Assuming for example that a motorist has run

out of gasoline at a point distant from a filling station and has brought a gallon of gasoline to his car in a combined funnel-container such as shown in Figure 1. He can pour this gasoline into his tank by simply removing the piece 15 of cord and rolling down the lower end of the stem 12 wherein it will take approximately the position shown by the dotted lines in Figure 1 because of pressure of the gasoline. It will be understood that the neck will be rolled down over the inlet of the gasoline tank and the gasoline line in the container can be emptied into the tank with little or no waste.

In Figure 3, is illustrated another form my invention may take when used for a special purpose. It is common to sell kerosene oil and sometimes gasoline in sheet metal cans C shaped substantially as illustrated in Fig. 3. Often the purchaser of a can of kerosene or gasoline has no funnel with him for emptying the contents of the can into the tank of his tractor or truck. To care for such a situation, a small size inexpensive form of my funnel generally designated as 20 can be made with a body 21 and single ear 23 provided with a hole through it large enough to engage around the usual short neck or spout member 24 of the can through which its contents are emptied. The solid line representation of the funnel 20 in Figure 3 is shown larger as regards the size of the can C than will ordinarily be the case in practicing my invention. This is done to better illustrate certain features of the funnel 20.

The engagement of the apertured ear 23 around the neck 24 serves a double purpose. It holds the funnel 20 in operative position relative to the can C. Also while in a flat condition, a funnel 20 of suitable size can be fastened by its apertured ear 23 to the usual neck member 24 of a can C so as to lie compactly on the usual flat top of the can as indicated by the dotted line portion of the funnel 20 in Figure 3. A funnel 20 and can C can be conveniently carried in stock as a unit and sold as a unit. The cost of the funnel to the dealer will ordinarily be quite low.

As illustrated in Figures 3 and 4, the funnel 20, may be constructed of two pieces of sheet metal and have two joints 25, one at each side, running from top to bottom. The engaging edges of the two pieces of sheet metal may be folded over and tightly fastened together along the lines of the joints 25 by a well known kind of crimping operation as indicated in Fig. 4.

If a funnel of the kind shown in Figures 3 and 4 is collapsed or flattened so as to have its two fold lines coincide with the lines of the two oppositely disposed joints 25, the pliable metal will need to be bent or folded through only about one half the angle as would be required if the fold lines came at other places than the joints 25.

To enable a collapsible funnel of either the Figure 1 or Figure 3 kind to give a maximum length of service, they should not be always collapsed along the same fold lines.

To open out a collapsed funnel which embodies my invention, the body 11 can be satisfactorily spread open with a person's hand since it is unnecessary to return it to an accurate conical form. To open out the stem 12, a pointed end of the stick S may be gently pushed through the stem, or a piece of strong cord or wire 26 may be tied to a piece of cloth 27 and the latter pulled through the pliable stem 12 as indicated in Figure 2. A narrow flat stick may be used to open the stem 12 by inserting it in the latter and turning the stick gently until the tube is suf-

ficiently open. Such a flat stick can be kept in a collapsed funnel.

It will be understood that when a funnel is constructed according to my invention to serve both as a funnel and as a large pail, the ears 13 should be made sufficiently strong for this service. This can be easily done by making the ears sufficiently large, or thicker than other portions of the funnel (see Figure 2). Also, the ears can be made of different and stronger material than the remainder of the funnel without departing from the scope of my invention.

Tourists and others may go for a long time without needing a funnel or pail but it is considered prudent to carry both since it can easily happen to any motorist that both of these articles will be greatly needed. It can be readily seen that according to my invention there is provided a collapsible funnel requiring but little space that can be manufactured to sell at such a low price that it will serve its purpose satisfactorily even if used but a few times in a long period. When my funnel has been made of pure soft sheet copper, it has lasted in practice over twelve collapsing and restoring operations.

Variations may be resorted to within the scope of the invention, and portions of the improvements may be used without others.

Having thus described my invention, I claim:

1. A metal funnel including a hollow discharge stem, said stem being sufficiently pliable to permit it to be folded back on itself by the user's finger so as to form a tight closure of the discharge outlet through said stem, whereby said funnel may serve temporarily as a container for fluids said stem being sufficiently pliable to permit it to be readily straightened thereafter for discharging said funnel of the fluids therein.

2. A funnel including a pliable metallic bowl-shaped body, an integral discharge stem made of metal sufficiently pliable to permit said stem to be folded back on itself by the user's fingers tightly enough to close said discharge stem against the escape of fluids in said body, and two ear members integrally joined to said body on opposite sides of the rim thereof, each ear having a hole for receiving a carrying member, whereby fluid may be carried in said funnel, said stem being straightenable and openable while the fluid is held in said funnel body above said stem, whereby the fluid may flow downwardly out of said funnel through said stem.

3. In combination, a funnel having a hollow, pliable discharge stem, a portion of said stem being folded back on itself to effect a tight closure of the discharge opening through said stem, and a fastening member arranged for holding said folded back stem portion in position to keep said discharge opening closed against the pressure of liquid in said funnel, said member being releasable while said funnel is maintained in an upright operative position, and said stem being readily unfolded while said funnel is maintained in said upright position, said stem being sufficiently pliable that the hydrostatic pressure of the liquid in said funnel will open up said flattened stem sufficiently to permit the discharge of the fluid therethrough.

4. A metallic funnel constructed of two pieces of pliable sheet metal, the edges of said pieces fastened together by crimping whereby two lengthwise joints are provided in said funnel from top to bottom on opposite sides of its axis, said funnel being foldable to a flat condition, the fold

lines coming substantially along said joints, whereby the angular extent of bending of the metal in said funnel when it is collapsed is largely reduced.

5. A metallic funnel constructed of two approximately equal pieces of flat pliable sheet metal, the adjoining side edges of said pieces being fastened together while said pieces are held in a flattened condition so that said funnel is completed while in a flat compact form, whereby said funnel is disposed in effective condition for

shipment to distributors, the metal of said funnel being sufficiently pliable to permit the purchaser of said flattened funnel to open up the same with his fingers alone to substantial operative position.

6. The structure described in claim 2 characterized by a stiff, relatively straight member being inserted through said ears for carrying said funnel.
